LIGHTING FIXTURE

Albert L. Judson, Portland, Oreg., assignor, by
mesne assignments, to On-A-Lite Corporation,
Peoria, Ill., a corporation of Oregon

Application February 14, 1949, Serial No. 76,211

5 Claims. (Cl. 339—99)

1

This invention relates to improvements in lighting fixtures of the type which are adapted to be mounted at random on an extension cord or the like without the use of tools.

The invention relates particularly to a type of fixture having a pair of contact prongs in the bottom of a conductor cord slot to pierce through the insulation of a twin conductor cord and establish electrical connection with the wires in the cord. The fixture has a body member and a cap and in most of the modifications disclosed the cap has screw threaded engagement with the body member and contains a relatively rotatable piston element adapted to enter into the slot in the body member and force the conductor cord onto the contact prongs when the cap is screwed on the body member. The cap also carries a mounting clip for attaching the lighting fixture to a Christmas tree branch or other support.

The general object of the present invention is to improve the construction of the cap for a fixture of the type referred to. A particular object is to provide improved means for securing the piston element and the mounting clip in the cap member, which means is inexpensive and easy to assemble, and which does not require the flexing or distortion of the piston element in order to insert it in the cap. Another object is to provide a novel form of retainer for insertion over the piston element to hold the piston element in the cap, while at the same time allowing for the free rotation of the piston in the cap. Another object is to make provision for limited rotation of the mounting clip so that it may be turned into alignment with a tree branch or other support without turning either the body or the cap of the fixture.

Other objects and advantages and details of construction are described in the following specification with reference to certain preferred embodiments of the invention illustrated in the accompanying drawings.

In the drawings:

Figure 1 is a longitudinal sectional view showing one form of the invention embodied in a lighting fixture of the type described;

Figure 2 is a perspective view of the cap of the fixture shown in Figure 1;

Figure 3 is a bottom plan view of the cap member to show the provision for limited rotation of the mounting clip;

Figure 4 is a fragmentary sectional view taken on the line 4—4 of Figure 3;

Figure 5 is a sectional view showing a cap member having a different form of retaining ring;

Figure 6 is a plan view of the retaining ring shown in Figure 5;

2

Figure 7 is a sectional view of a cap member showing another form of retaining ring; and

Figure 8 is a plan view of the retaining ring shown in Figure 7.

Figure 1 shows the general features of the type of lighting fixture to which the present invention pertains. The numeral 10 designates a body member of a synthetic plastic or other insulating material containing the usual metallic socket shell 11 which is screw threaded to fit a standard base on a light bulb 12, such as a decorative light used on Christmas trees and the like. The socket also has a central lamp contact 13, and these two contact elements are connected with a pair of metallic pins or prongs 14 and 15 projecting into the bottom of a transverse conductor cord slot 16 in the body 10. The slot 16 is of a width just equal to the width of common flat twin conductor cord, so that such cord may be disposed flat in the bottom of the slot without twisting. The prongs 14 and 15 are of sufficient length to pierce through one side of the usual rubber or plastic insulation on such cord, and they are spaced in the bottom of the slot to contact the stranded conductors in the cord when the cord is pressed over the prongs in the manner shown.

In connecting such a fixture, the conductor cord 17 is merely laid flat in the slot 16 across the points of the two prongs 14 and 15, and then a cap 20 having a rectangular piston element 21 is applied to the body 10 so that the piston element enters into the slot 16 and presses the conductor cord onto the prongs. The cap 20 has a cylindrical wall which is internally screw threaded at 22 for threaded engagement with the body, and the piston element 21 is rotatably mounted in the cap so that as the cap is screwed down on the body the piston element is forced to advance between the parallel walls of the slot, pushing the conductor cord ahead of it and onto the prongs. The piston element has a flat, circular base 23 to seat in the bottom of the cap, and the present invention is concerned with means to secure the piston element in the cap for free relative rotation.

In addition to forcing the conductor cord onto the prongs 14 and 15, the piston element 21 performs the further function of holding a mounting clip 25 in operative position in the cap for attaching the fixture to a convenient support. The clip 25 comprises two separate strips of spring metal, each having an inner end 26 bent at substantially right angles to its external part in order to lie flat against the inside surface of the cap, as shown. Interposed between the oppositely directed ends 26 and base 23 of the piston ele-

ment is a thin disc 27 forming a bearing element to facilitate free rotation of the piston element and to hold the end portions 26 flat against the inside of the cap. Further details of the mounting clip will be hereinafter described.

A principal feature of the present invention resides in the use of a retaining ring above the base 23 of the piston element to engage and wedge against the inner cylindrical wall of the cap member to hold the piston in the cap while permitting free relative rotation. Different forms of retaining ring for this purpose are shown in Figures 1, 6, and 8. The retainer shown in Figures 1, 2, and 4 comprises an annular ring 30 of flat springy material, such as brass. The ring 30 is dished to have a downwardly directed inner edge 31 disposed against the top surface of the base 23 and an upwardly directed outer edge 32 to be wedged into binding engagement with the inner wall of the cap. The outer edge 32 is preferably provided with sharp teeth or serrations 33 to bite into the material of the cap. The ring 30 may be secured in place, either by engagement of the outer edge 32 behind a turn of the thread 22 in the cap, or in a lower position by the biting of the teeth 33 directly into a smooth, cylindrical wall surface 34 below the end of the thread 22, as shown in Figure 4. Thus, the thread 22 may terminate a short distance above the end of the cap to leave smooth, cylindrical walls in the space beyond the end of the body 10 which is occupied by the base 23, clip ends 26 and disc 27.

In any event, regardless of the depth to which the thread 22 is formed, the retaining ring 30 is equally effective for this purpose and the parts are readily assembled by merely pressing the ring down into the cap with a suitable tool. If the outside diameter of the ring 30 is slightly larger than the inside diameter of the cylindrical wall or thread which it is to engage, the ring will be slightly contracted when it is pressed downward to its desired position so that when it is released to expand, its dished shape will cause its outer edge 32 to wedge firmly against the surrounding wall without causing its inner edge 31 to bind against the piston base 23 and interfere with rotation of the latter. The shoulder on the interior cylindrical wall of the cap, shown in Figure 4, serves as a stop to prevent jamming of the retaining ring tightly against the base of the piston element. While thus retained by the ring 30, the piston element 21 is capable of unlimited free rotation in the cap, and the mounting clip 25 is capable of limited rotation, as will be presently described.

In Figures 5 and 6, the retaining ring 40 is essentially a flat annulus of spring metal. Instead of the whole ring being dished like the ring 30 to expand to a diameter slightly exceeding the inside diameter of the cap wall, this ring has three projections 41 extending therefrom to engage the cap wall at only these three points. Thus, if the interior of the cap is threaded down to the top surface of the base 23, the projections 41 may bend to varying degrees to bindingly engage the groove of the spiral thread to make the ring secure. The piston element rotates freely under the ring.

Figures 7 and 8 illustrate a retaining ring taking the form of a round wire snap ring. The gap 46 between the ends of the wire is sufficient to permit contraction of the ring past the threads in the cap, but the relaxed diameter of the ring causes it to expand to seat firmly in the thread groove to retain the piston 21. The break in the

ring at 46 also permits the ring to deform the amount required by the pitch of the thread, so that the entire ring will lie in the thread groove as shown. The rounded surface of the wire permits the ring to be pressed through the threaded portion of the cap so that it does not have to be screwed into position.

The use of a resilient retaining ring, or snap ring, to secure the piston in the cap has a number of advantages. It permits the piston to be assembled in the cap by a simple direct movement without involving rotation of either of the parts. The retaining ring may be inserted along with the piston so that the use of this extra part reduces the number of manipulations and simplifies assembly. The use of a retainer ring also makes a variety of materials available for use in the piston element which are not naturally sufficiently flexible or otherwise deformable to permit the base of the piston to be contracted to pass the threads in the cap, and then expanded into an undercut groove as in a prior construction. Also, in addition to facilitating assembly, the use of a retainer ring obviates the necessity for forming an undercut groove to hold the base of the piston in the head of the cap. With the present form of construction, the circular base 23 of the piston has a diameter less than the internal clearance diameter of the threaded opening, and the internal wall portion of the cap surrounding the piston base may, therefore, be equal to or less than the clearance diameter through the threads. This simplifies the manufacture of the cap itself.

Another feature of the present construction is the provision for rotating the mounting clip 25 relative to the fixture without loosening the cap, so that in placing a string of the lights on a Christmas tree or the like each clip may be turned in the direction of the branch on which the fixture is to be mounted regardless of the direction of the cord. It will be apparent that a ninety degree rotation of the clip 25 is sufficient to enable it to be placed on a tree branch at any angle without objectionable bending of the cord. This amount of rotation is provided by making an opening 50 in the end of the cap of double sector shape to subtend approximately vertical angles of ninety degrees. The opening thereby has a projecting wall portion 51 to engage one side of the clip and a similar wall portion 52 to engage the other side of the clip, to center the clip in any position it may assume. These wall portions 51 and 52 engage not only opposite sides of the projecting spring arms but also the under sides of the bent end portions 26 to provide bearing surfaces under the full length of each end 26. With this form of construction, the clip is securely held so that it may be made in two pieces to facilitate assembly without losing the effectiveness of the spring action necessary to hold the fixture in an upright position on a support.

Having now described my invention and in what manner the same may be used, what I claim as new and desire to protect by Letters Patent is:

1. In an electrical fixture having a cap member with a piston element to force a conductor cord onto a pair of prongs to make electrical connection with conductors in said cord, an apertured end wall in said cap member, and a mounting clip extending through said aperture and having a portion inside of said cap clamped between the inside surface of said end wall and said piston element to hold the fixture upright when the clip is engaged with a support in an

upstanding position, said wall having portions defining said aperture in the general shape of a lemniscate wherein certain of said wall portions extend inwardly toward each other from opposite sides of said aperture to engage opposite sides of said clip and allow limited rotation of the clip in the aperture.

2. In an electrical fixture having a cap with a piston element to force a conductor cord onto prongs to make electrical connection with conductors in the cord, an apertured end wall in said cap, and a mounting clip for the fixture having a pair of flat resilient strips extending through said aperture and held within the cap by said piston element, said aperture being in the general shape of a lemniscate having opposed arcuate portions to permit limited rotation of said clip and having opposed projecting wall portions between said arcuate portions to engage opposite sides of the clip in different rotative positions of the clip.

3. In an electrical fixture of the type having contact prongs to pierce a conductor cord to make an electrical connection, a generally cylindrical cap for the fixture having a bottom end wall, a piston element in the cap having a flat generally circular base portion rotatably seated on said end wall to force the conductor cord against the prongs when the cap is applied to the fixture, a cylindrical wall portion of smaller interior diameter than the remainder of the cap extending from said end wall a distance greater than the thickness of said base portion of the piston element to form a shoulder in the cap, and a circumferentially inelastic and radially resilient retaining ring in the cap having a peripheral edge portion in radial binding engagement with the interior of said cap immediately above said shoulder and having another portion in axial engagement with said shoulder, said ring having a smaller inside diameter than said base portion of the piston element to retain said piston element in the cap, said shoulder preventing binding of the retaining ring against the piston element.

4. In an electrical fixture of the type having contact prongs to pierce a conductor cord to make an electrical connection, a generally cylindrical cap for the fixture having a bottom end wall, a piston element in the cap having a flat generally circular base portion rotatably seated on said end wall to force the conductor cord against the prongs when the cap is applied to the fixture, a cylindrical wall portion of smaller interior diameter than the remainder of the cap extending from said end wall a distance greater than the thickness of said base portion of the piston element to form a shoulder in the cap, and an annular, circumferentially inelastic radially resilient retaining ring of larger outside diameter than the inside diameter of the cap immediately above said shoulder, said retain-

ing ring being initially flat when unstressed and being sprung to dished shape in the cap with a peripheral edge portion of the ring in radial binding engagement with the interior of said cap immediately above said shoulder and the underside of the dished surface engaging said shoulder, said ring having an inside diameter smaller than said base portion of the piston element to retain said piston element in the cap, said shoulder preventing binding of the retaining ring against the piston element.

5. In an electrical fixture of the type having contact prongs to pierce a conductor cord to make an electrical connection, a generally cylindrical cap for the fixture having a bottom end wall, a piston element in the cap having a flat generally circular base portion rotatably seated on said end wall to force the conductor cord against the prongs when the cap is applied to the fixture, a cylindrical wall portion of smaller interior diameter than the remainder of the cap extending from said end wall a distance greater than the thickness of said base portion of the piston element to form a shoulder in the cap, a circumferentially rigid and radially resilient retaining ring in the cap having a peripheral edge portion in radial binding engagement with the interior of said cap immediately above said shoulder and having another portion in axial engagement with said shoulder, said ring having an inside diameter smaller than said base portion of the piston element retaining said piston element in the cap without binding the piston element, said end wall of the cap having a central aperture in the general shape of a lemniscate, and a spring mounting clip having a flat portion projecting through said aperture and having a portion clamped between the inside surface of said end wall of the cap and said base portion of the piston element to hold the fixture upright on the clip when the clip is engaged with a support in an upstanding position.
